DESIGN FOR A SUIT

Sydney Siegel, New York, N. Y.

Application March 13, 1940, Serial No. 90,891

Term of patent 3½ years

To all whom it may concern:

Be it known that I, Sydney Siegel, a citizen of the United States of America, residing in New York city, in the Borough of Manhattan, county and State of New York, have invented a new, original, and ornamental Design for a Suit, of which the following is a specification, reference being had to the accompanying drawing, forming part thereof, wherein,

The characteristic feature of my design resides in the combination on the jacket portion of the specific suit disclosed of the contrastingly colored buttons arranged at the shoulders as shown.

I claim:

The ornamental design for a suit, substantially as shown, and described.

SYDNEY SIEGEL.
